A technical drawing of a mechanical assembly, possibly a pump or valve, with various parts labeled with numbers. The drawing includes a central vertical column with a flange at the top, a horizontal pipe section, and a base. Numerous callouts with numbers point to specific features: 110, 50, 83, 48, 5, 55, 44, 45, 47, 49, 52, 53, 45, 54, 56, 72, 73, 74, 75, 76, 77, 78, 79, 80, 81, 82, 83, 84, 85, 86, and 87. The numbers are grouped into several clusters, with some numbers appearing in multiple callouts.

PNEUMATIC TELEGRAPH DEVICE

Adolph P. Gustofson, Chicago, Ill.

Application December 21, 1935, Serial No. 55,512

16 Claims. (Cl. 178—33)

This invention relates to telegraph devices and more particularly to improvements in translating devices therefor, although certain features thereof may be employed with equal advantage for other purposes.

It contemplates more especially the provision of novel message translating devices of the pneumatic type for use in connection with conventional electro-magnetic telegraph systems that determines and controls the operation thereof.

One object of the present invention is to provide pneumatic means for translating code signals into mechanical operations for transmission or reception of messages.

Another object is to provide novel pneumatic means for translating codified electrical impulses into mechanical movements for operating the keys of a typewriter or other suitable printing machine or similar device.

Still another object of the invention is to utilize pneumatically operated control valves for translating electrical message impulses into mechanical operations for message recordation in an improved and more effective manner.

A further object is to provide a series of interconnected valves comprising a pneumatic translating device of simple construction and dependable operation.

A still further object is to provide pneumatic translating devices which are instantaneously responsive to signal impulses for efficient, noiseless and rapid message recordation.

Still a further object is to provide a novel combination of pneumatically responsive valves and controls to comprise a comparatively inexpensive and extraordinarily rapid translating device for message reception and recordation.

Other objects and advantages will appear from the following description of an illustrative embodiment of the present invention.

In the drawings:—

Figure 1 is a schematic perspective view of a pneumatic translating device embodying features of the present invention.

Figure 2 is a schematic sectional view in elevation of the translating device shown in Figure 1.

Figure 3 is an enlarged sectional view taken substantially along line III—III of Figure 2.

Figure 4 is an enlarged sectional view taken substantially along line IV—IV of Figure 2.

Figure 5 is an enlarged sectional view taken substantially along line V—V of Figure 2.

Figure 6 is a plan view, partly in elevation and partly in section, of a code board comprising a

part of the translating device shown in Figure 1.

The structure selected for illustration comprises a pneumatic signal translating device which in its preferred form, includes the combination of a comparatively small number of 5 pneumatically operated index valves to selectively effect the operation of a comparatively larger number of independent pneumatically operated devices together with means for retaining the pneumatic valves in their operative positions until a signal translation has been effected and to, thereafter, quickly return the pneumatic valves to their initial position subsequent to effecting the operation of electro-magnetic means responsive to codified electrical impulses. 10 Additionally, such electro-magnetic means are utilized, in the present embodiment, for returning the operated parts of a pneumatically responsive translating device to initial position after each operation thereof. This results in a 15 substantially noiseless, rapid, and efficient signal translation device being provided.

More specifically, the structure selected for illustration comprises a circular distributor 8 which, in this instance, is divided into seven electrically insulated circumferentially arranged sections or segments numbered 1 to 7 for simplifying the illustration and clarifying the disclosure (see Figure 1). A distributor brush 9 is axially mounted for rotation in contact with the segments 1 to 7 of the distributor 8. The rotation of the brush 9 is in synchronism with a similar brush in an electrical transmitting device which may be of any standard or approved construction, but since it forms no part of this invention, it is not illustrated. A lead wire 10 extends from a grounded transmitting device and is connected to the brush 9 to provide the necessary circuit to the segments 1 to 7 leading to relays as will appear more fully hereinafter.

With the rotation of the brush 9 over the sections 1 to 7 of the distributor 8 by means of a suitable motor operatively connected therewith, the transmitting device sends impulses over the wire 10 to the brush 9 in a predetermined code. 45 It must be borne in mind, however, that in one complete rotation of the brush 9, one electrical impulse is only conducted to any one of the segments 1 to 6 as the brush 9 passes thereover. The seventh segment is for control purposes only as will appear more fully hereinafter. In consequence thereof, two, three, or as many as six electrical impulses may be imparted to the brush 9 as it rotates in contact with segments 1 to 7 of the distributor 8 during each revolution there-

of. These impulses are transmitted in accordance with a predetermined code to the first six segments of the distributor 8, and these codified impulses are pneumatically translated into mechanical movements for recordation through the medium of a printer, typewriter or other device suitable for that purpose as will appear more fully hereinafter.

It should be understood that the distributor 8 and brush 9 are merely illustrative of a device for distributing electrical signals or codified impulses from a transmitter, and any other suitable or standard distributor appliance may be substituted therefor without departing from or sacrificing any advantage of my invention which is directed to a pneumatic signal translating device that will be understood from the hereinafter described preferred embodiment serving to illustrate the principle rather than denote any precise instrumentalities as necessary to its physical embodiment.

As shown, conductors or lead wires 11 extend from each of the distributor sections 1, 2, 3, 4, 5, and 6 to a terminal 12 of a corresponding number of relays 13. The relays 13 are grounded through their other terminals 14 through the medium of lead wires 15 to complete the electrical circuit for transmitting and distributing the code signals. It is worthy of note that any other type of receiving or distributor device may be employed with equal or better advantage, since the distributor 8 is merely illustrative of the purpose and function of the source for electrical signals which are translated through pneumatically responsive instrumentalities into mechanical movements as will appear more fully hereinafter. Obviously, the relays 13 may be connected to any electric signal transmitting circuits such as the well known Mux or start-and-stop telegraph systems now in use in connection with various types of telegraph transmitters and distributors.

Each relay 13 includes a pivotally mounted armature 16 that has a connecting spring 17 anchored at the other extremity 18 thereof to normally displace or urge the armature 16 from the core 19 of each relay 13. As shown, the relay armatures 16 are provided with pneumatic control valves 20 on the free extremities thereof for displacement therewith responsive to the energization of the relays 13 or the springs 17 which are operative during the de-energization of the relays 13 to permit the separation of the armature 16 from contact with the relay cores 19 so that the valves 20 assume an extreme clockwise position (viewed from Figure 1) in contact with the open extremities 21 of the air tubes 22. A tube 22 is provided for each of the relays 13 and extends for communication with each of the chambers 23, in this instance six, closed by diaphragms 24 dividing the lower section 25 from an upper section 26 which are complementary to each other to define a primary valve block 27. Intermediate the lower section 25 and the upper section 26 of the primary valve block 27, is a longitudinal passage 28 which communicates with an air tube 29 for controlling the primary valve block 27 as will appear more fully hereinafter.

70 A motor driven vacuum pump or other suitable suction means 30 is provided with an intake housing 31 comprising the suction side of the pump 30 for communication with the conduit 29 leading to the primary valve block 27 so that a

vacuum is steadily maintained in the conduit 29 and its communicating passage 28 defined by both sections 25 and 26 and the sectional primary valve block 27. Bleeder ports 32 are provided in the lower valve block section 25 to connect the chambers 23 with the longitudinally chambered interior passage 28 of the primary valve block 27. Flexible diaphragms 24 constitute a wall of the chambers 23 and hermetically seal these from the passage 28, except for communication therebetween through the bleeder ports 32. So long as the relay valves 20 close the free ends of the tubes 16, a vacuum is maintained in the diaphragm sealed chambers 23 through the bleeder ports 32, thereby depressing or concavely drawing the diaphragms 24 into the suction chambers 23 (see Figure 2).

Now, then, valved openings or passages 33, in this instance six, are provided in the upper section 26 of the primary valve block 27 and extend transversely therethrough for communication with the interior longitudinal passage 28 which, in turn, has bleeder action with the chambers 23 through the ports 32. The valved openings 33 extend through the upper section of the primary valve block 27 for controlled exterior communication with the outside atmosphere by disc-shaped valves 34. The disc-shaped valve members 34 have surface liners 35 of yieldable material such as leather to contact the openings 33 around their peripheral edge which communicate with the outside atmosphere. The disc valves 34 are provided with axially extending rods 36 which extend through the openings 33 to terminate in convex valve heads 37 that conform in curvature with and confront the diaphragms 24. Reinforcing and leather inserts 38 are provided in the apex of the diaphragms 24 to contact the convex valve heads 37 so as to extend the normal life thereof and provide desirable operating characteristics thereof. Then, too, the flat surface 39 of the convex valve heads 37, are provided with liners 40 of yieldable material such as leather for coaction with the interior extremities of the openings 33 which communicate with the suction passages 28 of the primary valve block 27. Thus, when the valve members 34 have their liners 35 in closed contact with the top surface of the block section 26 to close the openings 33 from communication with the atmosphere, the convex valve heads 37 are displaced from the interior extremities of these same openings 33. Consequently, these openings 33 will, in this position of the valves 34-36-37, be in communication with the suction passage 28 so that a vacuum will exist therein. With the elevation of the valves 34-36-37, the valve surface 40 closes the openings 33 from the vacuum passage 28 and removes the valve surface 35 from the exterior peripheral edge of the openings 33, thereby by converting the openings 33 to atmospheric rather than vacuum influence.

75 A secondary valve block 41 is also provided with a corresponding number of chambers 42, in this instance six, formed in the lower section 43 that confronts an upper section 44 which are complementary to each other to define an intermediate longitudinal passage 45. A conduit 46 communicates with the passage 45 and like the conduit 29 of the primary valve block 27, extends 70 for communication with the intake housing 31 of the pump 30 to maintain a vacuum in the passage 45. The passage 45 is sealed from the chambers 42 by flexible diaphragms 47 to con-

stitute a wall of the chambers 42 and hermetically seal these from the passage 45.

Now, then, valved openings or passages 48, in this instance six, are provided in the upper section 44 of the secondary valve block 41 and extend transversely therethrough to terminate in reduced openings 49 which communicate with the interior longitudinal vacuum maintained passage 45. The valved openings 48 also extend through the top surface of the upper section of the secondary valve block 41, there being a plate 50 associated therewith to provide axially aligned openings 51 of reduced size corresponding substantially with the openings 49 and in registry therewith through the valved openings 48 for controlled exterior communication with the outside atmosphere by disc-shaped valves 52. The disc-shaped valve members 52 have surface liners or valve seats 53 of yieldable material such as leather to contact the openings 51 around their peripheral edge which communicate with the outside atmosphere. The disc valves 52 are also provided with axially extending rods 54 which extend through the aligned openings 48 and 49, the latter also being valved by a yieldable valve seat liner 55 on the opposite surface of the disc valves 52 which are, therefore, double acting.

The valve rods 54 terminate to confront the diaphragms 47 which have reinforcing and leather inserts 56 provided in the apex of the diaphragms 47 to contact the extremities of the valve rods 54 so as to extend the normal life thereof and provide effective operating characteristics therefor. Thus, when the valve members 52 have their seats 53 in closed contact with the top plate 50 of the upper block section 44 to close the openings 51 from communication with the atmosphere, the disc valves 52 with their seats 55 are displaced from the interior extremities of the lower openings 49. Consequently, these openings 49 will, in this position of the valves 52, be in communication with the suction passage 45 so that a vacuum will exist therein. With the descent of the valves 52, the valve seats 55 close the openings 49 from the vacuum passage 45 and removes the valve seats 53 from the interior peripheral edge of the openings 51, thereby converting the openings 49 to atmospheric rather than vacuum influence.

Another secondary valve block 57 is also provided with a corresponding number of chambers 58, in this instance six, formed in the lower section 59 that confronts an upper section 60 which are complementary to each other to define an intermediate longitudinal passage 61. A conduit 62 communicates with the passage 61 and like the conduits 29 and 46 of the primary and secondary valve blocks 27 and 41, respectively, extends for communication with the intake housing 31 of the pump 30 to maintain a vacuum in the passage 61. The passage 62 is sealed from the chambers 58 by flexible diaphragms 63 to constitute a wall of the chambers 58 and hermetically seal these from the passage 61.

In the main, the construction of this additional secondary valve block 57 is similar to the primary valve block 27, there being valved openings or passages 64, in this instance six, in the upper section 60 of this secondary valve block 57. The openings 64 extend transversely through the upper valve block section 60 for controlled exterior communication with the atmosphere by disc-shaped valves 65 which have yieldable seats 66 to contact the peripheral edge of the openings 64 to seal such from the atmosphere. The disc-

valves 65 are provided with axially extending rods 67 which extend through the openings 64 to terminate in convex valve heads 68 that conform in curvature with and confront the diaphragms 63 preferably provided with reinforcing leather inserts 69 positioned in the apex thereof to contact the convex heads 68. The convex valve heads 68 have a flat surface 70 provided with yieldable seats or liners 71 for coaction with the interior peripheral edges of the openings 64 which communicate with the suction passage 61. Thus, when the valve members 65 have their seats 66 in closed contact with the top surface of the valve block section 60 to close the openings 64 from the atmosphere, the convex valve heads 68 are displaced from the interior peripheral edge of these same openings 64.

Consequently, these openings 64 will, in this position of the valve members 65, be in communication with the suction passage 61 so that a vacuum will exist therein. With the elevation of the valve members 65, the valve seat 71 closes the openings 64 from the vacuum passage 61 and removes the valve seats 66 from the exterior peripheral edge of the openings 64, thereby converting these openings to atmospheric rather than vacuum influence. In other words, so long as a vacuum is drawn in the openings 64, the diaphragms 63 elevate the valve members 65 so that the valve seats 66 disengage the valve openings 64 to render such under the influence of atmospheric pressure. The operation and effect thereof will appear more fully hereinafter as these valve members 65 in conjunction with the others in the primary and first secondary blocks 27 and 41, respectively, are coordinated to enable the translation of the signal for recordation on mechanical devices which will be discussed infra. To this end, conduits 72 communicate between the valve openings 33 in the primary block 27 and the chambers 42 of the secondary block 41. The primary valve openings 33, in turn, communicate through conduits 73 with the chambers 58 in the auxiliary or additional secondary valve block 57.

Now then, a holding valve block 74 is provided with chambers 75, in this instance six, that are formed in the upper section 76 that confronts a lower section 77 to comprise the holding valve block 74. Diaphragms 78 close the chambers 75 and rest adjacent the surface of the lower block section 77, for operative communication with ports 79 that lead from conduits 80 in branched connection with the conduits 22 controlled by the relay operated valves 20. A suction passage 81 is provided longitudinally through the holding block 74 in the lower section 77 thereof and beneath the diaphragms 78. The suction passage 81 has by-passes 82 between this passage 81 and each of the chambers 75, and these by-passes 82 extend therefrom to a position below the diaphragms 78 therein for reasons which will appear more fully hereinafter. Conduits 83 interconnect the chambers 75 of the holding block 74 with the chambers 40 through ports 49 of the secondary valve block 41 for communication therewith above the diaphragms 78 therein.

A code block 85 has longitudinally extending channels 86 and 87 in each longitudinal segment 88 thereof, in this instance the code block comprises six longitudinal segments, and these are arranged in pairs for each longitudinal segment 88 as will appear more fully hereinafter. Code passages 89 extend transversely and interruptedly across the code block 85 (Figures 2 and 75

6). One branch of the code passages 89 leads from a longitudinally extending chamber 90 provided in a section 81 comprising part of the code block 85, to diaphragms 92 that close a plurality of code chambers 93 in a section 94 that is supplemental to the section 91 with the diaphragms 92 disposed therebetween. The chambers 93 above the diaphragms 92 are in communication with the channels 86. The next branch 95 of the passage 89 leads from the first code chamber 92 from beneath the diaphragm 93 to a succeeding code chamber 92 beneath its diaphragm 93, there being six segments 88 and each has its code chamber 92 so that these are interconnected as described supra by means of the branches or bypasses 95, 96, 97, 98, 99, and 100. As stated, the chambers 93 above their diaphragms 92 are in communication with the channels 86.

There are also a plurality of code chambers 101 provided in the section 94 of the code block 85, to communicate with the channels 87 in each code block segment 88. These are, in this instance, alternately disposed and arranged relative to the code chambers 92, and similarly therewith communicate with the longitudinal chamber 90 through conduits 102 that extend to diaphragms 103 that close the code chambers 101. Then branches or by-passes 104, 105, 106, 107, 108, and 109 interconnect the code chambers 101 in a manner similar to the by-passes 95, 96, 97, 98, 99, and 100 that interconnect the code chambers 93; however, the code chambers 93 communicate with the longitudinal channel 86 while the code chambers 101 communicate with the longitudinal channel 87 in each of the block segments 88, and the code chambers 93 and 101 of each code block segment 88 are reflectively interconnected by by-passes 95 to 100 and 104 to 109 inclusive. Now, then, the conduits 83 that interconnect the chambers 48 and 75 of the secondary valve block 41 and the holding block 74, respectively, have extension passages 110 provided, in this instance, between the secondary block 41 and the section 94 of the code block 85, to communicate with the longitudinal channels 86 (Figure 2). Conduits 111 extend between the valve chambers 64 in the auxiliary or additional secondary block 57 to communicate with the longitudinal channels 87 in each segment 88 of the code block section 94.

When the translating device is at rest, the channels 86 are in communication with the atmosphere, and a vacuum is present in the channels 87. Thus, the code passages 89 are closed together with their by-passes 95 to 100 because the diaphragms 92 in the code chambers 93 are seated to close all possible communication therein while the diaphragms 103 in the code chambers 101 which communicate with the channels 87 are unseated so that communication is established between the by-passes 104 to 109 that open therein. This difference in the position of the diaphragms 92 and 103 is due to the exertion of atmospheric pressure on the seated diaphragms 92 and the influence of a vacuum on the unseated diaphragms 103. Reversal of these positions is a matter of valve operation in the various blocks 27, 41, and 57 as well as the control effected by the holding block 74 which responds to the code block 85. The various code chambers 92 and 101 are arranged in different combinations so that, for example, their respective diaphragms are seated or unseated to respond to different signal impulses from the distributor 8 and to detect such for corresponding translation

for operating a printer or other receiver. It will be apparent that a large number of varied arrangements and combinations of the code chambers 92 and 101 are possible and, further, additional code capacity may be accomplished by reversing the conditions in the channels 86 and 87 so that a vacuum may be drawn in the channel 86 of each segment 88 and the channel 87 thereof may be connected for communication with the atmosphere. Moreover, this reversal of the conditions in the channels 86 and 87 may be effected in a single or in any number of segments 88 so that various combinations may be resorted to for increasing the capacity of the code block 85 to substantially a limitless value.

The arrangement of the diaphragms 93 and 103 and the possible alternating of the conditions in the channels 86 and 87 in different segments 88 of the code block 85 renders such possible, simple, and efficient. Although a very large number of combinations are possible, in the present instance however, only forty-five combinations are utilized. Consequently, forty-five transverse code passages 89 and 102 are provided in the code block 85. Individual conduits 115 extend from each of the terminal by-passes 100 and 109 which communicate with the last code chamber 92 and 101 in each code block segment 88 of the code block 85, to establish connection with diaphragm chambers 116 in a bellows block 117 of a pneumatically operated printer or other receiver 118. A diaphragm 119 is provided in each chamber 116 and separates such from a suction chamber 120 in each bellows block 117. A bleeder passage 121 establishes communication between the diaphragm chamber 116 and the suction chamber 120 in each block 117. A bellows 122 is mounted on the upper side of each block 117. A spring 123 is connected thereto for suitable attachment to a fixed part of the device such as the frame to normally hold the bellows distended. A port 124 is provided in each block 117 to establish communication between the interior of the bellows 122 and a valve body opening 125 which has a valved port 126 providing communication therefor with the suction chamber 120.

Another port 127 is provided in the block 117 above the valve body opening 125 to provide access to the atmosphere, there being a valve 128 in the opening 125 to control the ports 126 and 127 for opening or closing responsive to the action of the diaphragm 119 that cooperates with a rod 129 extending axially from the disc valve 128. The disc valve 128 has a valve seat 130 to cooperate with the port 126 closing the suction passage 120 from the bellows 122 and opening the port 127 to subject such to atmospheric influences when the valve 128 is displaced downwardly. When the valve 128 ascends from its downward position (shown in Figure 2) to establish communication between the chambers 120, and 124, the bellows 122 is under suction influence and collapses against the urge of the spring 123. The suction chambers 120 are connected with the pump 30 through a conduit 131 that is in communication with its housing 31, and each of the bellows 122 is provided with a link 132 that is connected to a key arm 133 of a pneumatic typewriter or other receiving device 118.

The presence of atmospheric influence in the conduit 115 (Figure 2) causes the diaphragm 119 to move upwardly by reason of the vacuum in chamber 120 and, thereupon, the valve 128 as-

cends to close the port 127 and opens the port 126. Thereupon a vacuum is created in the port 124 to collapse the bellows 122. The collapsing of the bellows 122 is utilized to actuate the key arm 133 connected thereto, thereby impressing a letter that corresponds with the electric signal received from the distributor 8 and translated to a mechanical movement on the receiver 118. It should be noted that the link 132 can be connected to any suitable device depending upon the dictates of commercial practice and the use to which the teachings of the present invention is contemplated. When predetermined code signals are received on a receiving device (to be described infra) and the corresponding solenoids 13 are actuated, the various diaphragms 92 or 103 in one code passage 86 or 87 will all be unseated to admit pressure into a conduit 115 connected to this particular code passage. Therefore, the diaphragm 119 in the receiver block 117, will elevate the valve 129 to close the port 127 and open the port 126 to create a vacuum in the bellows 122, effect its collapse, and actuate the key arm 133 to print 25 the letter corresponding with the signal responsible for the operation thereof.

It has been explained that the valves 65 in the auxiliary secondary block 51, are normally positioned to establish communication between 30 the openings 64 and the suction passage 61; consequently, a suction or vacuum is provided in these openings 64. The conduits 111 connect the openings 64 with the longitudinal channels 87 in each code block segment 88 so that a vacuum is normally present in the longitudinal channels 87 of the code block 85. Furthermore, the passages 110 extend from the openings 48 in the secondary block 41 to the channels 86 in each code block segment 88. Since these openings 48 normally communicate with the atmosphere, it is apparent that atmospheric pressure is normally admitted to the channels 86 while a suction or vacuum is normally present in the channels 87 in the segments 88 of the code block 45 85. It is also worthy of note that the transverse code passages 89 and 102 admit pressure into the conduits 115 leading therefrom to normally distend the bellows 122. This occurs under the control of instrumentalities that will now be explained.

A conduit 135 leads from the chamber 91 in the block 85 to a passage 136 in a control block 137. A suction chamber 138 is provided in the block 137 for termination in a conduit 139 that communicates with the pump 30. Consequently a vacuum is normally drawn in the chamber 138, and communication between this chamber 138 and the passage 136 is normally established through a valved opening 139. A valve member 140 is disposed in the opening 139 to normally assume a closed position admitting suction or a vacuum influence to the chamber 138 so that the valve head 141 normally closes the opening 139 from the atmosphere. A chamber 142 is provided in the block 137 and a diaphragm 143 is provided therefor to control the valve member 141 through its axial rod 144. A vacuum is normally drawn in the diaphragm chamber 142 through a bleeder port 145 that communicates 70 with a passage 146 which terminates in the diaphragm chamber 142.

A conduit 147 leads from the diaphragm chamber 142 and the terminal open end thereof is normally closed by a valve member 148 on the 75 armature 149 owing to the urge of a spring 150

connected thereto (Figure 1). The armature 149 is pivoted to cooperate with an electro-magnet 150 which has one end 151 of its winding connected to the seventh section of the distributor 8 through a wire 152. The other end 153 of the solenoid winding 150, is grounded as at 154. With each revolution of the brush 9 of the distributor 8, an electric impulse passes from a conductor 155 leading to an independent source of current, through the brush 9 and distributor 10 section 7 to the winding of the solenoid 150 to operate the valve member 140 in the control block 137 which functions after the signal pulses in the first six sections of the distributor 8 have been translated as will appear more fully hereinafter.

As shown, a conduit 156 leads from the passage 136 to a bellows 157 that is normally collapsed against the action of a spring 158, since a vacuum is drawn therein by reason of communication 20 thereof with the passage 136. The bellows 157 is connected to an arm 159 having a trip finger projection 160 that is normally urged into engagement with a confronting trip projection 161 on a valve arm 162 owing to a spring 163. The 25 arm 162 carries a valve 164 that is urged by the spring 163 into closing position over the open end of a conduit 165. The conduit 165 leads to a diaphragm chamber 166 in a second control block 167. The chamber 166 has a diaphragm 168 provided 30 therein to control the operation of a valve member 169 disposed in an opening or valve chamber 170 that has reduced ports 171 and 172, the port 171 communicating with a suction passage 173. The suction passage 173 is provided in 35 the block 167 for connection with the pump 30 through a conduit 174. The port 172, on the other hand, communicates with the atmosphere. Another passage 175 is provided in the block 167 for communication with the valve chamber 170 40 which is connected with the suction passage 81 in the holding valve block 74 through a conduit 176. A bleeder port 177 connects the diaphragm chamber 166 with the suction passage 173. The valve chamber 178 is normally in communication with 45 the atmosphere through the port 172, the valve member 169 closing the port opening 171 through which communication may be established between the suction passage 173 and the valve chamber 170 when the valve 169 ascends responsive to the diaphragm 168 to close the port 172 leading to the atmosphere.

Now, then, such of the key operating bellows 122 comprising part of the receiver 118, are actuated responsive to their individual code chambers 93 55 and/or 101 which are selectors of electrical signals reaching the solenoids 13 that have armatures 16 cooperating with the air tubes 22 for translating electrical impulses to pneumatic actions which control the bellows 122. The seventh 60 pulse solenoid 150 controls the other pulses after signal recordation has been effected to restore them to initial position in a cycle of operations that will now be explained. Actuation of any one or more of the key arms 133 for recording signals 65 or messages, requires suction to be established in the bellows 122 (Figure 2) corresponding therewith and connected thereto. The normally distended diaphragms 92 in a corresponding code passage 89 and its successive branches provided for the code 70 block 85, will be retracted and the normally retracted diaphragm 92' will remain retracted in order that pressure may be admitted to the conduits 115 leading to the selected bellows 122. Hence, the valve 34 in the primary block 21 con- 75

trolling diaphragms 92 will be operated while the primary valves 34' controlling diaphragms 92', will remain in normal position. In order to effect this selection, electrical signal impulses must pass through the sections 1, 2, 3, and 5 of the distributor 8 as the brush 9 contacts therewith so that the solenoids 13 connected therewith will be energized. Consequently, the energized solenoids 13 will lift their armature valves 20 from the open ends of their tubes 22 leading to the diaphragm chambers 23 having the diaphragms 24 for actuating the valves 34. This occurs in that the diaphragm chambers 23 are opened to the atmosphere to destroy the vacuum previously present in these chambers 23. As a result, the diaphragms 24 will be convexly flexed to elevate the valves 34 through their rods 36 that are operatively connected to the diaphragms 24 through the medium of their heads 37.

More specifically, when the vacuum is destroyed in these chambers 23, the vacuum in the passage 28 will enable air admitted in the aforementioned diaphragm chambers 23 to move the diaphragms 24 upwardly to correspondingly elevate the valve members 34. This will close communication between the openings 33 and the passage 28 in the primary valve block 27, and air is admitted into these openings 33 around the elevated valves 34. Therefore, air is also admitted into the diaphragm chambers 42 in the secondary valve block 41 thereby elevating the diaphragms 47 in these chambers 42 inasmuch as a vacuum is present in the passage 45. When these secondary diaphragms 47 flex upwardly, the valves 52 are also elevated and communication between the valve openings 48 and the atmosphere is closed-off. These valve openings 48 then communicate with the passage 45 so that a vacuum is created therein. Inasmuch as the longitudinal chambers 86 in the code block section 94 are in communication with the corresponding valve openings 48 in the secondary valve block 41, a vacuum will be drawn in the code chambers 93 so that the diaphragms 92 are convexly flexed or retracted to establish communication between the longitudinal chamber 90 and conduit 115 inasmuch as the diaphragms 92 do not move from their illustrated positions by reason of the fact that their primary control valves 34' are not operated in this cycle of code combinations corresponding to the signals that are responsible for such a selection.

At the same time air is admitted through conduits 73 into the corresponding chambers 58 of the auxiliary secondary valve block 57; therefore, the diaphragms 63 in these chambers 58 flex upwardly to elevate the valves 65. This shuts off communication between the valve openings 64 and the suction passage 61. As a result, air is admitted into these valve openings 64 for passage 60 through conduits 111 into longitudinal channels 87 to destroy the vacuum normally present in these channels. Simultaneously with the creation of a vacuum in the longitudinal channels 86, a vacuum is provided in the chambers 75 of the holding block 76 so that the diaphragms 78 are unseated. This establishes communication between the suction passage 81 in the holding block 76 and the tubes 80 leading from the conduits 22 that communicate with the diaphragm chambers 23 normally under a vacuum influence. At this time the passage 81 is in communication with the atmosphere through the conduit 116, the valve chamber 169 and port opening 172 of the control block 167. Consequently, even though the 75 solenoid operated armature valves 20 which were

initially unseated from the ends of the tubes 22 become reseated, which occurs as soon as the brush 9 passes from contact with the respective distributor sections 1 to 7 connected to the solenoids controlling the valves 20, air is admitted into these tubes 22 so that the above described instrumentalities which were rendered operative when the valves 20 were unseated, are held in the positions they have attained owing to the action and control exercised by the holding block 10 74.

Normally a vacuum is created in the longitudinal chamber 90 inasmuch as its conduit 135 communicates with the passage 136 that in turn communicates with the suction chamber 138 through 15 the valved opening 139 of the control block 137. However, as explained, when all of the diaphragms in any particular code passage 89 or 102 are unseated, pressure is to be admitted into the bellows 122 communicating with this particular code passage through a conduit 115. This is accomplished as the brush 9 passes over the section 7 at the end of each revolution thereof, for the seventh pulse solenoid 150 is then energized 20 so that the armature valve 148 (Figure 1) is unseated from the free end of the tube 147. Consequently air is admitted in this tube 147 for entry into the diaphragm chamber 142 of the control block 137 wherein a vacuum was previously present. Therefore, the diaphragm 143 30 flexes convexly upwardly to elevate the valve member 140 which closes the valve opening 139 and opens the port 139. Air is, therefore, admitted through the port 139 into the passage 136 and through the conduit 135 into the longitudinal 35 chamber 90 and through the opened code passage 89 or 102 in the code block 85 to the diaphragm chamber 116 of the receiver bellows block 118. Thereupon the diaphragm 119 in the receiver bellows block 118 is moved upwardly to elevate the 40 valve 128 for closing the port 127 and opening the port 126 to establish a vacuum in the chamber 124. The bellows 122 will then collapse and move the link 132 downwardly to operate the key arm 133 connected thereto. 45

Air admitted into the passage 126 of the control block 137 to pass through the conduit 156 for entry into the bellows 157 which expands to displace the trip 160 over the confronting cam surface 161 to interpose a delay sufficient to enable operation of the bellows 122 as described supra. However, as soon as the trip 160 has moved a predetermined distance over the cam surface 151, the valve 164 is unseated from the free end of the tube 165 and air is, therefore, admitted into the diaphragm chamber 166 of the control block 167 to move the diaphragm 168 upwardly. This elevates the valve 169 so that the port 172 is closed and the port 171 is opened for establishing communication between the valve chamber 170 and the suction passage 173. Therefore, a vacuum is drawn in the valve chamber 170 and the conduit 176 so that the previously unseated diaphragms 78 in the chambers 75 of the holding block 74 are subjected to a vacuum and reseated to assume their initial positions (Figure 2). Thereupon, further introduction of air into the tubes 22 is precluded, and a vacuum is again drawn in the diaphragm chambers 23 so 70 that the valves 34 are reseated to assume their initial positions shown in Figure 2. Consequently, other instrumentalities control these valves 34 to their initial positions in readiness for another cycle of operations predicated on electrical sig- 75

nals that are handled by the distributor 8 during successive revolutions of the brush 9.

It will be apparent that the seventh pulse solenoid valve 148 like the solenoid operated valves 20, is unseated only momentarily for as soon as the brush 9 has passed from the distributor section 7, the solenoid 150 is de-energized and the spring 150' reseats the valve 148. This shuts off any further admission of air into the diaphragm chamber 142 of the control block 137 and, thereupon, a vacuum is again drawn in this chamber 142 by reason of its communication with the suction chamber 138 through the bleeder passage 145. Hence, the valve 140 is quickly returned to its initial position as shown in Figure 2 so that a vacuum is again drawn into the passage 136 to collapse the bellows 157 to allow the springs 163 to return the arms 159 and 162 to the positions illustrated in Figure 1. The valve 164 will, therefore, shut off the admission of air into the tube 169 with the result that a vacuum is again drawn in the diaphragm chamber 166 to return the valve 169 to its initial position shown in Figure 2.

As soon as the initial position is re-established in the longitudinal channels 86 and 87 of the code block section 94, the admission of air to the conduit 115 is closed and, therefore, a vacuum is again drawn in the receiver bellows block diaphragm chamber 116 by reason of its communication with the suction passage 120 through the bleeder passage 121. Thus, the valve 128 is returned to its initial position shown in Figure 2 and air is admitted into the chamber 124 so that the bellows 122 distends or expands with the aid of the spring 123. It will thus be seen that all instrumentalities will be promptly returned to their initial positions after a cycle of operations so that the device will be ready to translate the next code signal received by the distributor 8. Thus a translating device embodying a large number of combinations has been provided to quietly, speedily, dependably, and efficiently receive and record messages with any suitable type of receiver 118. Since the signal translation is pneumatically effected, it is capable of rapid and positive operation and the possibility of failure is reduced to a minimum. Furthermore, by eliminating a complicated wiring system, the location of any defect in the event of failure is simplified and capable of speedy correction.

Various changes may be made in the embodiment of the invention herein specifically described without departing from or sacrificing any of the advantage of the invention or any features thereof, and nothing herein shall be construed as limitations upon the invention, its concept or structural embodiment as to the whole or any part thereof except as defined in the appended claims.

I claim:—

1. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves.

2. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves, a primary valve block having pneumatically operated valves corresponding with the number of solenoids for pneumatic connection with said code block.

3. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves, a primary valve block having pneumatically operated valves corresponding with the number of solenoids for pneumatic connection with said code block, a secondary valve block having pneumatically operated valves corresponding in number with said primary valves for pneumatic connection therewith.

4. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves, a primary valve block having pneumatically operated valves corresponding with the number of solenoids for pneumatic connection with said code block, a secondary valve block having pneumatically operated valves corresponding in number with said primary valves for pneumatic connection therewith, another secondary valve block pneumatically connected to the aforesaid valve blocks.

5. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves.

tributor through said solenoid operated valves, a primary valve block having pneumatically operated valves corresponding with the number of solenoids for pneumatic connection with said code block, a secondary valve block having pneumatically operated valves corresponding in number with said primary valves for pneumatic connection therewith, another secondary valve block pneumatically connected to the aforesaid valve blocks, a holding valve block for interposing delay in the action of the valves in said primary and secondary valve blocks.

6. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, pneumatic means in communication with said tubes for translating electrical signals to mechanical movements, said pneumatic means including a code valve block having a plurality of pneumatically operated valves for selecting the signals from said distributor through said solenoid operated valves, a primary valve block having pneumatically operated valves corresponding with the number of solenoids for pneumatic connection with said code block, a secondary valve block having pneumatically operated valves corresponding in number with said primary valves for pneumatic connection therewith, another secondary valve block pneumatically connected to the aforesaid valve blocks, a holding valve block for interposing delay in the action of the valves in said primary and secondary valve blocks, and solenoid operated pneumatic means for restoring said code block, primary block, secondary blocks and holding block to initial valve positions.

7. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, pneumatic means in communication with said tubes for translating electrical signals to mechanical movements, said pneumatic means including a code valve block having a plurality of pneumatically operated valves for selecting the signals from said distributor through said solenoid operated valves, a primary valve block having pneumatically operated valves corresponding with the number of solenoids for pneumatic connection with said code block, a secondary valve block having pneumatically operated valves corresponding in number with said primary valves for pneumatic connection therewith, another secondary valve block pneumatically connected to the aforesaid valve blocks, a holding valve block for interposing delay in the action of the valves in said primary secondary valve blocks, solenoid operated pneumatic means for restoring said code block, primary block, secondary blocks and holding block to initial valve positions, and pneumatic receiver means operatively responsive to said solenoids and pneumatic valve block means.

8. In a device of the character described, the combination with an electrical distributor, of a plurality of armature operating solenoids electrically connected to said distributor, a plurality of air valves associated with the armatures of said

solenoids, air tubes mounted so that their free ends confront said armature valves for opening and closing said tubes, and pneumatic means in communication with said tubes for translating electrical signals to mechanical movements, a holding block for interposing delay in the action of the valves in said primary and secondary valve blocks.

9. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves, a holding valve block for interposing delay in the action of the valves in said primary and secondary valve blocks.

10. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, and pneumatic means in communication with said tubes for translating electrical signals to mechanical movements, said pneumatic means including a code valve block having a plurality of pneumatically operated valves for selecting the signals from said distributor through said solenoid operated valves, a primary valve block having pneumatically operated valves corresponding with the number of solenoids for pneumatic connection with said code block, a holding valve block for interposing delay in the action of the valves in said primary and secondary valve blocks.

11. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, pneumatic means in communication with said tubes for translating electrical signals to mechanical movements, a holding block for interposing delay in the action of the valves in said primary and secondary valve blocks, and pneumatic receiver means operatively responsive to said solenoids and pneumatic valve block means.

12. In a device of the character described, the combination with an electrical distributor, of a plurality of armature operating solenoids electrically connected to said distributor, a plurality of air valves associated with the armatures of said solenoids, air tubes mounted so that their free ends confront said armature valves for opening and closing said tubes, pneumatic means in communication with said tubes for translating electrical signals to mechanical movements, said pneumatic means including a code valve block having a plurality of pneumatically operated valves for selecting the signals from said distributor through said solenoid operated valves, a holding valve block for interposing delay in the

action of the valves in said primary and secondary valve blocks, and pneumatic receiver means operatively responsive to said solenoids and pneumatically operated valve block means.

5 13. In a device of the character described, the combination with an electrical distributor, of a plurality of armature operating solenoids electrically connected to said distributor, a plurality of air valves associated with the armatures of said 10 solenoids, air tubes mounted so that their free ends confront said armature valves for opening and closing said tubes, pneumatic means in communication with said tubes for translating electrical signals to mechanical movements, said 15 pneumatic means including a code valve block having a plurality of pneumatically operated valves for selecting the signals from said distributor through said solenoid operated valves, a primary valve block having pneumatically operated 20 valves corresponding with the number of solenoids for pneumatic connection with said code block, a holding valve block for interposing delay in the action of the valves in said primary and secondary valve blocks, and pneumatic receiver 25 means operatively responsive to said solenoids and pneumatically operated valve block means.

14. In a device of the character described, the combination with an electrical distributor, of a 30 plurality of armature operating solenoids electrically connected to said distributor, a plurality of air valves associated with the armatures of said solenoids, air tubes mounted so that their free ends confront said armature valves for opening 35 and closing said tubes, pneumatic means in communication with said tubes for translating electrical signals to mechanical movements, said pneumatic means including a code valve block having a plurality of pneumatically operated 40 valves for selecting the signals from said distributor through said solenoid operated valves, a primary valve block having pneumatically operated valves corresponding with the number of solenoids for pneumatic connection with said 45 code block, a secondary valve block having pneumatically operated valves corresponding in number with said primary valves for pneumatic connection therewith, another secondary valve block 50 pneumatically connected to the aforesaid valve blocks, a holding valve block for interposing delay in the action of the valves in said primary and secondary valve blocks, and solenoid operated pneumatic means including a control valve for restoring said code block, primary block, secondary blocks and holding block to initial valve 55 positions.

15. In a device of the character described, the combination with an electrical distributor, of a plurality of armature operating solenoids electrically connected to said distributor, a plurality of air valves associated with the armatures of said 5 solenoids, air tubes mounted so that their free ends confront said armature valves for opening and closing said tubes, pneumatic means in communication with said tubes for translating electrical signals to mechanical movements, said 10 pneumatic means including a code valve block having a plurality of pneumatically operated valves for selecting the signals from said distributor through said solenoid operated valves, a primary valve block having pneumatically operated 15 valves corresponding with the number of solenoids for pneumatic connection with said code block, a secondary valve block having pneumatically operated valves corresponding in number with said primary valves for pneumatic connection therewith, another secondary valve block 20 pneumatically connected to the aforesaid valve blocks, a holding valve block for interposing delay in the action of the valves in said primary and secondary valve blocks, and solenoid operated 25 pneumatic means including interconnected control valves for restoring said code block, primary block, secondary blocks and holding block to initial valve 30 positions.

16. In a device of the character described, the combination with an electrical distributor having a plurality of signal pulse conducting segments therein, a final pulse conducting segment on said distributor, solenoids connected to the segments of said distributor, said solenoids having armatures, air tube valves associated with said solenoid armatures, air tubes having their open ends extending in confronting relation with said valves to open and close said tubes responsive to the energization and de-energization of said solenoids, a pneumatic receiver for recording signals transmitted to said solenoids through said distributor, pneumatic means interposed between said solenoid controlled air tubes and said receiver to translate electrical signals into mechanical movements for operating said pneumatic receiver, and pneumatically operated valve means responsive to said final pulse conducting segment to restore said first named pneumatic means and receiver to initial position for repeated response to said distributor pulse transmitting segments in successive cycles of signal transmission thereto.

ADOLPH P. GUSTOFSON. 55
